CLAIM

The ornamental design for a granular feed packaging, as shown and described.

DESCRIPTION

FIG. 1 is a front, left-side perspective view of a granular feed packaging showing our new design;

FIG. 2 is a front, right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a perspective view of the granular feed packaging in an alternative configuration; and,

FIG. 10 is a perspective view from another angle of view of FIG. 9.

1 Claim, 8 Drawing Sheets
